UNITED STATES PATENT OFFICE.

LEVI K. FULLER, OF BRATTLEBOROUGH, VERMONT, ASSIGNOR TO THE
ESTEY ORGAN COMPANY, OF SAME PLACE.

DESIGN FOR AN ORGAN-CASE.

SPECIFICATION forming part of Design No. 15,433, dated October 7, 1884.

Application filed May 31, 1884. Term of patent 14 years.

To all whom it may concern:

Be it known that I, LEVI K. FULLER, a citizen of the United States, and a resident of Brattleborough, Windham county, Vermont, 5 have invented or produced a new and original Design for an Organ-Case, of which the following is a specification.

My design has relation to the cases of what are known as "chapel-organs," which are 10 finished both in front and at the back, and it is clearly represented in the accompanying photograph, wherein Figure 1 is a perspective view of the case, showing the front; and Fig. 2, a similar view, showing the back.

15 Referring to Fig. 1, A is the key-board projection, and B B are the ends of the case. C is the cover, which is shown as raised in this figure. The key-board projection A is furnished, as usual, with an open-work strip or 20 panel in its front. In my design the ornamentation of this panel consists of a rectangular elongated opening, in which is a central disk bearing a quarterfoil, and two horizontal bars, arranged midway of the opening, extend from the ends of the same to said disk 25 and join it. The open-work consists of two of the above-described designs. On each end of the case is an ornament, D, comprising a base, a, of ornamental contour, a beaded cap, 30 b, a pediment, c, and a ball, d. This ornament is designed to present the same appearance when viewed from the front and back of the case.

Referring to Fig. 2, E is the back board of 35 the case. F is an inclined panel above the back board, and G is the top board of the case. The back board, E, is divided into panels e e e, all ornamented alike. A description of one will suffice. The panel is divided 40 unequally into three parts by two pairs of horizontal lines or marks, and in the cen-

tral compartments is a lineal design composed of an endless line arranged to form a square, which stands oblique in the panel, and has lesser squares at its corners. Between these 45 lesser squares are dots, four in number, all as clearly shown in Fig. 2. The panel F is ornamented with open-work, which comprises a rectangular elongated opening in which are arranged rings g, having a broken ornamental 50 contour, and connected together by horizontal ties or bars h, all as clearly shown in the accompanying photograph. Below and above the panel F are horizontal beaded bands i i.

Having thus described my design, I claim 55 as its novel features—

1. In an organ-case, the design which consists of the ornamentation of the open-work panel in the front of the key-board projection A, as shown in the accompanying photograph. 60

2. In an organ-case, the design which consists of an ornament, D, on each end of the case, of substantially the form and configuration described, and shown in the accompanying 65 photograph.

3. In an organ-case, the design which consists of the back board, E, divided into panels e e e, as shown, and said panels having the linear ornamentation, substantially as described, and shown in the accompanying photograph. 70

4. In an organ-case, the design which consists of an inclined panel, F, above the back board, said panel being ornamented with open-work, as shown in the accompanying photograph. 75

In witness whereof I have hereunto signed my name in the presence of two subscribing witnesses.

LEVI K. FULLER.
